UNITED STATES PATENT OFFICE

128,033

DESIGN FOR A SWEATER

Louis Meyers, Cedarhurst, N. Y.

Application February 24, 1941, Serial No. 99,172

Term of patent 3½ years

To all whom it may concern:

Be it known that I, Louis Meyers, a citizen of the United States, residing at Cedarhurst, in the county of Nassau and State of New York, have invented a new, original, and ornamental Design for a Sweater, of which the following is a specification, reference being had to the accompanying drawing, forming part thereof.

The figure is a plan view of a sweater showing my new design.

The dominant feature of the design consists in the relatively wide knitted ruffle ornamentations above and around the shoulder portions, in the form of epaulettes, the latter being arranged at the ends of the ribbed yoke and extending both

at front and back to approximately the same height, and a similar knitted ruffle ornamentation of lesser width surrounding the neck portion and comprising a horizontal ruffle bar in front of the neck and a loop encircling the back and sides of the neck, the sides of the loop extending at the front vertically downwards for a substantial distance below the horizontal bar.

The back of the sweater is similar to the front, except that only the top loop portion of the neck ruffle is visible.

I claim:

The ornamental design for a sweater, as shown and described.

LOUIS MEYERS.
